UNITED STATES PATENT OFFICE

140,209

DESIGN FOR AN OBSERVATION CAR BODY

Jane E. Goodykoontz, Kansas City, Mo.

Application June 5, 1944, Serial No. 113,857

Term of patent 7 years

(Cl. D14—3)

To all whom it may concern:

Be it known that I, Jane E. Goodykoontz, a citizen of the United States, residing at Kansas City, in the county of Jackson and State of Missouri, have invented a new, original, and ornamental Design for an Observation Car Body, of which the following is a specification, reference being had to the accompanying drawing, forming part thereof.

Fig. 1 is a perspective view of an observation car body, taken from the rear showing my new design.

Fig. 2 is a side elevational view.

Fig. 3 is a top plan view.

Fig. 4 is a front elevational view thereof.

The opposite side of the design of the observation car is the same as the side illustrated in Figs. 1 and 2.

I claim:

The ornamental design for an observation car body, as shown and described.

JANE E. GOODYKOONTZ.
